VENTILATOR OPERATING MECHANISM FOR AWNING TYPE WINDOWS

Ralph D. Shaw, Sr., Miami, Fla.

Application January 13, 1956, Serial No. 559,066

1 Claim. (Cl. 268—110)

Summarized briefly, the present invention is a ventilator for an awning type window, which ventilator is mounted to swing outwardly from and inwardly toward the frame of the window between open and closed positions respectively.

The device includes a vertically movable connecting bar mounted in each side of the frame and held in place by a shield adapted to afford protection against the elements in the open position of the ventilator, and further adapted to hold the connecting bar in place and permit the use of headless pivot pins. Pivots connected to the upper end of the connecting bar is an extension plate connected to the adjacent side of the ventilator, and constituting lever means for imparting a force to the ventilator tending to swing the same outwardly or inwardly, depending upon the direction of movement of the connecting bar, with the swinging movement being controlled by the link pivotally connected between the frame and ventilator.

At each side of the window, a cable is connected at its opposite ends to the upper and lower end portions of the connecting bar, through the medium of a suitable tension-adjusting bracket, and said cable is trained over sheaves within the frame, with the cables at both sides of the frame being controlled by gear means conjointly rotatable by a user. Associated with the gear means is a construction which will permit slippage of the gear means when the ventilator has reached the extreme limits of its travel, to prevent damage to the device.

Ordinarily, a ventilator of a window of this type includes a cross shaft, together with arms, links, bearings, shims, shoulder screws, etc. Such a construction is relatively complex and is expensive not only to manufacture but also to install. Still further, in conventional mechanisms of this type, operational deficiencies have become apparent. A twisting action is imparted to the ventilators, and this occasionally causes the glass to crack. Further, the conventional construction makes imperative an adjustment of the links, accomplished through an adjustable link anchor which in turn requires elongated slots in the frame. Still further, in all mechanisms employing a cross shaft there is outward thrust of the connecting bar against the lower guide, tending to produce excessive friction, which friction is increased in proportion to the extent to which the ventilator is opened. Then again, in conventional construction, there is provided a bulky mechanism, exposed to view.

The main object of the present invention is to provide a generally improved ventilator operating device, having none of the deficiencies described above.

Other objects will appear from the following description, the claims appended thereto, and from the annexed drawing, in which like reference characters designate like parts throughout the several views, and wherein:

Figure 1 is a view of an awning type window equipped with a ventilator and ventilator-operating mechanism formed in accordance with the present invention, por-

2

tions being broken away and other portions being shown in section;

Figure 2 is a transverse sectional view on line 2—2 of Figure 1; and

5 Figure 3 is a vertical sectional view substantially on line 3—3 of Figure 1.

Referring to the drawings in detail, the reference numeral 10 generally designates the frame of an awning type window. The frame 10 is of generally channel shaped cross section including (Figure 2) outer and inner side walls 12, 14 connected by a web 16. An outwardly directed flange 18 formed on outer side wall 12 is engaged by the outer edge of the ventilator sash 20, the frame of the ventilator having an inwardly directed flange 22 bearing against an inner flange 23 formed on side wall 14 of the window frame. The ventilator frame includes side portions 24, on the opposite edges of which the flanges 20, 22 formed, with said flanges 20, 22 extending in opposite directions from the portion 24.

20 As will be noted from Figure 2, this provide a rectangular housing defined by the stationary window frame 10 and the vent frame 20, 22, 24. Said housing is closed when the ventilator is in closed position, and to prevent exposure of the ventilator operating mechanism to the elements when the ventilator is open there is fixedly mounted in the frame a flanged shielding plate 26 secured by fastening elements 28 to outer side wall 12.

25 The swinging movement of the ventilator frame between open and closed positions is effected through the medium of an elongated, straight link 30 (Figure 3) pivotally connected at its opposite ends by headless pivot pins 32 to the ventilator frame and window frame respectively. A lever plate or pad 34 is fixedly secured at its lower end at 35 to the upper portion of the ventilator frame, and is connected at its upper end to the upper end of a vertically slidably actuating bar 36, through the medium of a headless pivot pin 38.

30 To the lower end of bar 36 is connected an angle bracket 40, having a rotatable element 42 capable of being secured by a lock screw in selected positions of rotatable adjustment. One end 44 of an operating cable is coiled about the element 42, and extends downwardly from bracket 40 about an idler sheave 46. In the lower portion of the window frame, the cable is trained about a drum 48 having closely spaced peripheral grooves 50, 52 each of which is the width of the operating cable so that the cable will be wound upon the drum in a plurality of convolutions disposed one upon another in a common plane. Cable 44 is wound within groove 50, and similarly 45 coiled in groove 52 is an actuating bar lifting cable 54 trained at the lower corner of the window frame about an idler sheave 56. At the upper end of the window frame cable 54 is trained about an upper idler sheave 58, and is then connected to a cable tensioning bracket 60 50 secured to the upper portion of actuating bar 36, bracket 60 having a rotatably adjustable element 62 similar to the element 42. To effect rotation of drum 48, there is provided a shaft 64 journaled in the lower portion of the window frame medially between the sides of the frame. Crank means, not shown, would be attached to the right hand end of the shaft viewing the same as in Figure 3.

55 Secured to the shaft 64 for rotation therewith is a pinion 66 in mesh with gears 68, 70 disposed at opposite sides of the pinion and secured to stub shafts journaled in the window frame, for rotation with said stub shafts, which have been designated at 71, 73 respectively.

60 To lock the gears and pinion in selected positions to which they are rotated, there is provided a lock roller housing 74, secured to the window frame interiorly of the building structure. Shaft 64 extends through hous-

ing 74, and secured to shaft 64 for rotation therewith within the housing is a peripherally toothed lock roller 76 against which bears an axially shiftable detent 78 biased toward the roller by means of a spring 80 held under compression in a spring retainer cup 82 threaded in housing 74. Shims 83 may be inserted in the cup for increasing the tension of spring 80 to a selected extent.

Ordinarily, on rotation of shaft 64, detent 78 will not hold lock roller 76 against rotation, since the inner or roller-engaging end of the detent is continuously biased out of the notches of the roller during rotation, as long as the detent is free to shift axially in a direction away from the lock roller. However, when the ventilator has been opened or closed to a selected extent, one may thread into engagement with the plunger or detent a locking screw 84. This will hold the plunger against movement out of engagement with an associated notch, thereby preventing rotation of pinion shaft 64.

The drum 48 associated with each gear is freely rotatable upon the shaft 71 or 73, as the case may be, and is biased into frictional engagement with the associated gear by a compression coiled spring 86 the tension of which may be regulated by a collar 88 bearing against the spring and formed upon an adjusting sleeve mounted in a bearing bracket 90 stationarily mounted in the lower portion of the window frame.

The sleeves 92 are threaded, for the purpose of adjusting said sleeves in an axial direction, to vary the compression of the spring 86, and this in turn adjusts the force with which the spring bears against a pressure plate 93, forcing said pressure plate against the drum 48.

In this manner, the drum is rotatable with its associated shaft, responsive to rotation of the meshing gears 66, 68, 70, but should excessive resistance to rotation develop, as for example when the ventilator has reached one or the other of the extreme limits of its travel, the drum will slip relative to the shaft, so that continued rotation of the shaft will not result in rotation of either drum.

It will be seen that with a mechanism such as has been illustrated and described herein, mounted at opposite sides of the window frame, rotation of the single shaft 64 will adjust the bars 36 at opposite sides of the frame upwardly or downwardly, as the case may be, for the purpose of opening or closing the window.

When the bars 36 are shifted downwardly, downward pressure will be exerted upon the ventilator frame through the medium of the connection of the lever plate 34 to said ventilator frame. This will be translated into outward swinging movement of the ventilator frame, due to the fact that downward pressure exerted thereon tends to swing the links 30 outwardly at their upper ends.

It is important to note that when the ventilator frame is open, the operating mechanism is still concealed, due to the provision of the shield or partition 26.

Further, the shield has the effect of facilitating installation of the assembly, since it serves as a retainer for the actuating bar 36 and for the link 30 of each side of the window. This enables the use of headless

5 pivot pins, and consequently, by removing a section of the shield adjacent any particular ventilator, the ventilator may be readily removed.

It is believed apparent that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles, it being considered that the invention comprehends any minor change in construction that may be permitted within the scope of the appended claim.

What is claimed is:

- 15 In an awning type window construction, an open front window frame formed to a channel shaped cross section including outer and inner side walls and a web connecting the side walls; a sash including an inwardly directed flange, the inner side wall of the window frame including a flange against which the flange of the sash bears in the closed position of the sash, said sash further including an outwardly directed flange closing the open front of the window frame in the closed position of the sash; a shielding plate extending transversely within the 20 window frame to prevent exposure of the interior of the window frame in the open position of the sash; a link connectable pivotally between said frame and sash and arranged for swinging the sash outwardly and inwardly responsive to downward and upward pressures, respectively, exerted on the sash; an actuating bar adapted for vertically slidable movement in opposite directions within said frame and having a connection to the sash adapted for transmitting said downward and upward pressures to the sash responsive to vertical movement of the actuating bar in opposite directions; and remote control means 25 adapted for operation by the user for effecting said vertical movement of the actuating bar, said shielding plate having a fixed connection along one side thereof to the outer side wall of the window frame, the shielding plate arranged for swinging the sash outwardly and inwardly responsive to downward and upward pressures, respectively, exerted on the sash; an actuating bar adapted for vertically slidable movement in opposite directions within said frame and having a connection to the sash adapted for transmitting said downward and upward pressures to the sash responsive to vertical movement of the actuating bar in opposite directions; and remote control means 30 adapted for operation by the user for effecting said vertical movement of the actuating bar, said shielding plate having a fixed connection along one side thereof to the outer side wall of the window frame, the shielding plate arranged for swinging the sash outwardly and inwardly responsive to downward and upward pressures, respectively, exerted on the sash; an actuating bar adapted for vertically slidable movement in opposite directions within said frame and having a connection to the sash adapted for transmitting said downward and upward pressures to the sash responsive to vertical movement of the actuating bar in opposite directions; and remote control means 35 adapted for operation by the user for effecting said vertical movement of the actuating bar, said shielding plate having a fixed connection along one side thereof to the outer side wall of the window frame, the shielding plate arranged for swinging the sash outwardly and inwardly responsive to downward and upward pressures, respectively, exerted on the sash; an actuating bar adapted for vertically slidable movement in opposite directions within said frame and having a connection to the sash adapted for transmitting said downward and upward pressures to the sash responsive to vertical movement of the actuating bar in opposite directions; and remote control means 40 adapted for operation by the user for effecting said vertical movement of the actuating bar, said shielding plate having a fixed connection along one side thereof to the outer side wall of the window frame, the shielding plate arranged for swinging the sash outwardly and inwardly responsive to downward and upward pressures, respectively, exerted on the sash; an actuating bar adapted for vertically slidable movement in opposite directions within said frame and having a connection to the sash adapted for transmitting said downward and upward pressures to the sash responsive to vertical movement of the actuating bar in opposite directions; and remote control means 45 adapted for operation by the user for effecting said vertical movement of the actuating bar, said shielding plate having a fixed connection along one side thereof to the outer side wall of the window frame, the shielding plate arranged for swinging the sash outwardly and inwardly responsive to downward and upward pressures, respectively, exerted on the sash; an actuating bar adapted for vertically slidable movement in opposite directions within said frame and having a connection to the sash adapted for transmitting said downward and upward pressures to the sash responsive to vertical movement of the actuating bar in opposite directions; and remote control means 50 adapted for operation by the user for effecting said vertical movement of the actuating bar, said shielding plate having a fixed connection along one side thereof to the outer side wall of the window frame, the shielding plate arranged for swinging the sash outwardly and inwardly responsive to downward and upward pressures, respectively, exerted on the sash; an actuating bar adapted for vertically slidable movement in opposite directions within said frame and having a connection to the sash adapted for transmitting said downward and upward pressures to the sash responsive to vertical movement of the actuating bar in opposite directions; and remote control means 55 adapted for operation by the user for effecting said vertical movement of the actuating bar, said shielding plate having a fixed connection along one side thereof to the outer side wall of the window frame, the shielding plate arranged for swinging the sash outwardly and inwardly responsive to downward and upward pressures, respectively, exerted on the sash; an actuating bar adapted for vertically slidable movement in opposite directions within said frame and having a connection to the sash adapted for transmitting said downward and upward pressures to the sash responsive to vertical movement of the actuating bar in opposite directions; and remote control means 60 adapted for operation by the user for effecting said vertical movement of the actuating bar, said shielding plate having a fixed connection along one side thereof to the outer side wall of the window frame, the shielding plate arranged for swinging the sash outwardly and inwardly responsive to downward and upward pressures, respectively, exerted on the sash; an actuating bar adapted for vertically slidable movement in opposite directions within said frame and having a connection to the sash adapted for transmitting said downward and upward pressures to the sash responsive to vertical movement of the actuating bar in opposite directions; and remote control means
